COVERED SUGAR BOWL

Efrem M. Ostrowsky, Highland Park, Ill., assignor to Jules P. Gits and Joseph A. Gits, both of River
Forest, Ill.

Application October 10, 1957, Serial No. 48,045

Term of patent 14 years

(Cl. D44—15)

FIG. 1

FIG. 3

Fig. 1 is a plan view of a covered sugar bowl embodying my design;

Fig. 2 is a side elevational view of the bowl of Fig. 1; and

Fig. 3 is an end elevational view of the bowl of Figs. 1 and 2.

I claim:

The ornamental design for a covered sugar bowl, as shown.
